D. D. POWELL

CLAMP

Filed Jan. 2, 1924

Daniel D. Powell
INVENTOR

BY Victor J. Evans

J. J. L. Wright

WITNESS:

ATTORNEY

UNITED STATES PATENT OFFICE.

DANIEL D. POWELL, OF SEAGRAVES, TEXAS.

CLAMP.

Application filed January 2, 1924. Serial No. 684,018.

To all whom it may concern:

Be it known that I, DANIEL D. POWELL, a citizen of the United States, residing at Seagraves, in the county of Gaines and State 5 of Texas, have invented new and useful Improvements in Clamps, of which the following is a specification.

This invention has reference to a pipe clamp.

10 The object is to simplify and improve the existing construction by producing a device of this character which will effectively grip a pipe to prevent the turning thereof, and wherein the parts are so constructed that the 15 greater the effort of the turning of the pipe, the more effectively the same will be gripped.

To the attainment of the foregoing, the invention consists in the improvement as hereinafter described and definitely claimed.

20 In the drawing:—

Figure 1 is a view illustrating a pipe clamped in accordance with this invention.

Figure 2 is a view showing the movable section of the clamp swung for the reception 25 of a pipe between the jaws thereof.

Figure 3 is a plan view of the improvement.

Figure 4 is a sectional view on the line 4—4 of Figure 3.

30 Figure 5 is a perspective view of the removable and adjustable jaw.

The clamp includes a fixed section 1 and a movable section 2.

The fixed section 1 preferably has its sides 35 gradually widened from its inner to its outer edge, and the body portion of the said section between the sides 3 thereof has its inner edge concaved, as at 4, and if desired, toothed or serrated to engage with a pipe 5.

40 The portion 4 provides the jaw of the fixed section 1. The sides 3, at their inner ends are bifurcated to receive therein tongues 6 formed on the sides 7 of the section 2. Removably pivoted pins 8 pass through the 45 sides 3 and through the tongues 6 of the section 2. The sides 7 of the section 2 are connected together by a body plate 9 and the said sides have their outer edges provided with aligning series of notches 10 whose

50 walls are arranged at a downward and outward inclination. Within two of the align-

ing notches there is designed to be received laterally extending lugs 11 formed on the tail portion of the adjustable jaw 12. The tail portion of the said jaw has its under 55 face rounded, as at 13, and its opposite active end is concaved and formed with transverse teeth 14.

In practice, one of the pins 8 is removed and the movable section 2 swung on the second pin to one side of the fixed section 1. The pipe 5 is then arranged for contacting with the jaw 4 of the fixed section and the movable section is swung closed and the pin 60 is again inserted to lock the movable section to the fixed section. The jaw 12 has its lugs arranged in any pair of the aligning notches 10 and is then swung against the pipe to firmly hold the same in the clamp.

While I have illustrated a satisfactory 70 embodiment of my improved device, my features of invention are capable of extended application and I do not wish to be limited to the specific structure shown and described.

Having described the invention, I 75 claim:—

1. A pipe clamp comprising a fixed section and a movable section, means pivotally securing the sides of the movable section to the sides of the fixed section, said fixed section, 80 between its sides having a jaw portion, and a removable and adjustable jaw trunnioned between the sides of the movable section, for the purpose set forth.

2. A pipe clamp comprising a fixed section whose sides extend beyond the inner face of the body thereof and are bifurcated, and the said face of the body providing a jaw, and a movable section including a plate having upstanding sides provided with 85 tongues received in the bifurcated ends of the fixed section and removably pivoted therein, the sides of the last mentioned section having downwardly directed outwardly inclined aligning notches, a jaw comprising 90 a block-like member having lugs on its sides adjacent to its outer end to be received in aligning notches in the sides of the last mentioned section and said jaw having its inner 95 face concaved and toothed.

In testimony whereof I affix my signature.

DANIEL D. POWELL.
